OR D 14,838

No. 14838

MARCH 4, 1884

UNITED STATES PATENT OFFICE.

RODOLPHE CHRISTESEN, OF NEW BRITAIN, CONNECTICUT, ASSIGNOR TO
RUSSELL & ERWIN MANUFACTURING COMPANY, OF SAME PLACE.

DESIGN FOR A LAMP-BRACKET.

SPECIFICATION forming part of Design No. 14,838, dated March 4, 1884.

Application filed August 6, 1883. Term of patent 7 years.

To all whom it may concern:

Be it known that I, RODOLPHE CHRISTESEN, a citizen of the United States, residing at New Britain, in the county of Hartford and 5 State of Connecticut, have invented and produced a new and original Design for a Lamp-Bracket, of which the following is a specification, reference being had to the accompanying drawings, forming part thereof.

10 Figure 1 is a side elevation of the main portion of my newly-designed bracket, and Fig. 2 is a front elevation of the base-plate or companion part for the portion shown in Fig. 1.

15 Near the middle of the base-plate A is the bracket-socket *a*, the front of which is ornamented by a raised ledge and leaflets. The raised borders upon the base-plate, at the two 20 sides of the socket *a*, are in imitation of ropes coiled at each end. Extending vertically through the middle of the base-plate, and apparently underneath the socket *a*, is a raised ledge which terminates in a ring at the top and in the flukes of an anchor at the base, 25 which parts, with the cross-bar *b*, form the figure of an anchor on the front of the base-plate A, as shown. The lower portion of the bracket B presents a contour in side view in the shape of a boat or gondola. Near the middle 30 of the length of the boat are two projections, *c c*, which represent an oar-lock, and extend-

ing obliquely through said oar-lock is an ornament, *C*, in the form of an oar or paddle. At the bow of the boat-shaped bracket is an upright, *d*, surmounting which is the cup *D* 35 for the lamp, or, if desired, for a flower-pot or other article, the design for the bracket being the same no matter what article may be supported by it. From the part which represents the stern of the boat there rises a curved 40 brace, *g*, and connected therewith is the horizontal and vertical bars *e* and *f*, respectively. The upper end of the oar or paddle *C* is connected with the lower end of the vertical bar *f*. The sides of the various parts of the bracket 45 and cup are ornamented in relief, as shown.

I claim—

1. In a bracket, the design for the main portion B, as herein shown and described.
2. In a bracket, the design for the main portion B and the cap D, as herein shown and described.
3. The design for a bracket herein shown and described, the same consisting of the shape and ornamentation of the cap D, the main portion B, and the base-plate A, bearing the representation of an anchor.

RODOLPHE CHRISTESEN.
